UNITED STATES PATENT OFFICE.

RICHARD H. WELLES, OF KENOSHA, WISCONSIN, ASSIGNOR TO THE BADGER BRASS MANUFACTURING COMPANY, OF KENOSHA, WISCONSIN, A CORPORATION OF WISCONSIN.

DESIGN FOR A VEHICLE-LAMP.

40,747.

Specification for Design.

Patented June 28, 1910.

Application filed March 21, 1910. Serial No. 550,810. Term of patent 7 years.

To all whom it may concern:

Be it known that I, RICHARD H. WELLES, a citizen of the United States, residing at Kenosha, in the county of Kenosha and State of Wisconsin, have invented a new, original, and ornamental Design for Vehicle-Lamps, of which the following is a specification, reference being had to the accompanying drawings, forming a part thereof.

In the drawings,—Figure 1 is a perspective view of my new design, and Fig. 2 is a top plan view of the same.

The salient or distinguishing features of the design may be briefly described as follows: A cube-like main body portion 1 is pro-

vided with a plurality of glass openings. To the bottom of the main body is connected an oil font 2 of the generally polygonal exterior configuration shown. Surmounting the main body is a tier of top ventilators 3—3 likewise of polygonal configuration and decreasing in radial width toward the top of the tier.

I claim:

The ornamental design for a vehicle lamp, as shown and described.

RICHARD H. WELLES.
